SYNCHRONIZER TO INTRODUCE ARTICLES IN PROPER PHASE

Benedict R. Benith, Westbury, N.Y., assignor to American Machine & Foundry Company, a corporation of New Jersey

Filed Oct. 1, 1962, Ser. No. 227,158
4 Claims. (Cl. 83—201,12)

This invention relates in general to slicing machines, particularly to an infeed synchronizing arrangement for high speed bread slicing machines using endless band saw blades and dual sets of pushers for driving the loaves positively and continuously through the blades without disengagement from one or the other set.

An object of the invention is the improvement of bread slicing machines.

Another object of the invention is the provision of a synchronizing mechanism in the infeed of a high speed bandsaw bread slicing machine, which machine is equipped with dual sets of pusher flights, to positively push each loaf entirely through the blades without disengagement therefrom, which synchronizing mechanism introduces the bread into the path of the first pusher flight in the input of the machine at the optimum time for engagement with the first pusher flight.

In the present machine, the two sets of pusher flights are operated continuously. One set engages the loaf near the upper rear surface thereof and pushes the loaf partially through the multiple blades which are inclined at an obtuse angle to the surface on which the oncoming loaf is supported. The second set of pusher flights is synchronized with the first and engages the lower rear surface of the loaf after it has moved forward to a position clear of the blades and while the first flight is still in engagement with the upper portion of the loaf and pushes it through the remaining distance to clear the blades and then through the outfeed of the machine. In order to promote proper slicing, it is desirable that the loaf be presented to the first pusher flights at the proper time in a cycle. In the present invention this is performed by an improved mechanism in the infeed of the slicer. This improved mechanism receives loaves incoming to the slicer at random and presents each loaf in the path of a set of flights in the first pusher at the precise moment for proper engagement therewith, so that the slicing operation may be controlled by the two sets of synchronized pusher flights and the bread may be correctly sliced. It should be obvious that unless the engagement between the loaf and the multiple blades is properly controlled slicing will be inaccurate and at times may be so faulty that the loaf is unsaleable.

In the present arrangement, the loaves incoming at random through the infeed of the machine are propelled onto the horizontal surface of a displaceable element which is normally fixed in position, but which may be pushed vertically to raise the loaf into the path of the first pusher flights disposed at a higher level in the machine. As each loaf is propelled onto the vertically displaceable element the loaf engages a tripping mechanism. The tripping mechanism enables a cam operated lever mechanism the operation of which is synchronized with the flight mechanism. At the proper instant, after the enabling of the cam operated lever mechanism, the lever is actuated to raise the vertically displaceable element to raise the loaf into the path of the oncoming pusher flights. The vertically displaceable surface or platform, hereinafter termed an elevator, is then lowered to its normal unoperated position, and the cam actuated lever mechanism is thereupon disabled. This cycle is repeated as each loaf is received on the elevator.

A feature of the invention is a mechanism, normally

2

disabled, responsive to the reception of a loaf of bread, to enable a cyclically operated mechanism to present the loaf to another mechanism at the proper phase in the cycle of operation of the other mechanism.

5 Many other objects, advantages and features of the invention reside in the construction, combination and arrangement of parts involved in the embodiment of the invention as will be understood from the following description and accompanying drawings wherein:

10 FIG. 1 is a vertical section taken longitudinally through the machine;

FIG. 2 is a plan view partly in section of a portion of the machine;

15 FIG. 3 is an enlarged vertical section of a portion of the machine showing the loaf elevator and the controls therefor; and

FIGS. 4, 5 and 6 are vertical longitudinal partial sections of the machine showing the bread elevator in three different positions.

20 The present invention represents an improvement in a bread slicing machine widely used and well known in the baking industry and also described in my pending patent application, Serial No. 34,561, filed June 7, 1960, now U.S. Patent No. 3,096,892. It is considered, therefore, that it is not necessary to describe well known parts thereof in detail and they will be described herein only insofar as is necessary to an understanding of the present invention.

25 Referring to the drawings in detail, the bread slicing machine is constructed as follows. As shown in FIG. 1, a motor 10, drives a belt 11 which turns a pulley 12 mounted on a shaft 13 which is rotatably journaled in the sides of frame 14.

30 On each side of the top of frame 14 there is slidably mounted a bearing block 15 in which a shaft 16 is rotatably mounted to carry a blade support drum 17. Two retracting mechanisms 18 are connected by means of a shaft 19 which may be turned to slide both the blocks 15 in relation to the frame 14 to move the drum 17 toward or away from the drum 12 and thus adjust the tension of the bandsaw blades whose path is indicated by the broken line 20. The two deflecting idler drums 21 and 22 are rotatably secured by means of the shafts 23 and 24 which are journaled in opposite sides of frame 14.

35 40 45 The blades 20 each form a distorted figure 8 passing over, around and under the drive drum 12, over the deflecting roller 22, under the deflecting roller 21, over, around and under the idler roller 17 and back over the driver roller 12. Since the blades 20 must lie flat against the drums when they contact them, each blade receives a 180 degree twist between drum 22 and drum 23 as well as between drum 17 and drum 12.

50 An infeed head generally designated by the numeral 39, FIG. 1, is slidably mounted between the side members 55 of the frame 14 to be positioned by means of the handle 31 and the screw thread 32 a desired distance above an infeed table 32 to accommodate loaves of any desired height within a range. The upper blade guides 33 and the lower blade guides 34 are mounted between the frame 60 sides 14. These blade guides 33 and 34 may be laterally adjusted to regulate the thickness of the bread slices. Such adjustable blade guides may be of the type shown in Patent No. 2,293,083 issued August 18, 1942 to P. G. Schlemmer or Patent No. 2,375,231, issued May 8, 1945 to A. A. Kottmann or in accordance with my patent application, Serial No. 34,561. The present machine is preferably driven by the same drive as is an associated packaging machine, not shown, so that the two machines may be operated in synchronism. In the present drawings, an 65 individual motor 40 is shown as being the driving source. It is emphasized that this single source is used to drive all of the moving parts in the slicing machine, except 70

the slicing blades, so as to facilitate the synchronization of its various coacting parts. Motor 40 drives chain 41 which turns the shaft 42 clockwise. Shaft 42 carries sprocket 43 which drives the endless chain 44. Chain 44 extends about the sprockets 43, 45, 46, 47, 48, 49, 50 and back to 43. Mounted on the same shaft as sprocket 49 and integral therewith, as shown in the upper middle portion of FIG. 1, is sprocket 60 which through chain 61 drives sprocket 62 mounted on shaft 63 which is journaled in opposite sides of the head 30. Another shaft 64 is also journaled in the opposite sides of head 30 near its front end. Integral with shaft 63 near its opposite ends are a pair of sprockets such as 66 and integral with shaft 64 near its opposite ends are a pair of sprockets such as 68. The sprockets 66 and 68 are interconnected by endless chains indicated by 70 which carry the infeed flights such as 72, 74, 76, 78, 80 and 82 generally counterclockwise. The flights are shown in various positions they assume under the influence of gravity and the camming action of their followers in engagement with the cammed surfaces as is well known in the art.

Integrally mounted on shaft 42 and driven also by sprocket 43 is sprocket 90 which through chain 92 drives sprocket 94 which is secured to shaft 95 journaled in opposite sides of the outfeed generally indicated at 96. Integral with shaft 94 near its opposed ends are a pair of sprockets which drive a pair of chains such as 98. The chains pass about a pair of sprockets such as 100 secured to a shaft 102 journaled in opposite sides of the outfeed 96 and then through guide ways in outfeed 96, over a pair of sprockets, such as 104, secured near the opposed ends of shaft 105, which is journaled in the opposed sides of outfeed 96, and over sprockets such as 6 back to sprockets 94. The outfeed flights which engage the lower rear surface of each loaf, after the loaf has been pushed through the blades, so that the lower rear surface is clear of the blades, are secured to the chains such as 98.

As mentioned in the foregoing, chain 44 drives sprocket 47 and, as best seen in FIGS. 2 and 3, integrally mounted on the same stud with sprocket 47 is sprocket 150 which drives chain 152 which in turn drives sprocket 154. Integral with sprocket 154 is sprocket 156 which drives chain 158. Chain 158 drives sprockets 160, 162, and 164. Cam 103, which controls the elevator mechanism, in a manner to be described hereinafter, is mounted integrally on the same stud as that on which sprocket 162 is secured.

Mounted integrally on the same stud to which sprocket 164 is secured, as seen in FIG. 3, is sprocket 170. Sprocket 170 drives chain 172 which drives sprocket 174. Sprocket 174 is secured to shaft 175 which is journaled in opposite sides of the frame of infeed 32. Drum 176 is integrally mounted on shaft 175 and drives drum 178 through the continuous bread infeed belt 180. Drum 178 is secured to shaft 179 which is journaled in the opposite sides of the infeed 32. Belt 180 is driven in such direction that it moves the bread loaves such as 190 and 192 from left to right as seen in FIGS. 1 and 3.

At the right-hand end of the bread infeed run, as seen in FIG. 3, are two elevator platforms 124 and 126. The horizontal portion of platform 124 is larger than and overlies that of 126. The two platforms are supplied to afford some flexibility to accommodate loaves of different sizes. If desired, platform 124 may be used alone for smaller loaves and platform 126 may be removed. Platform 124 is secured at each side to brackets 120 and 122.

Supported in a bracket integral with each side of the frame is shaft 134 from which tripping plate 128 depends. Secured to the frame behind plate 128 is stop spring element 130 and stop 132 both of which are adjustable by means of screws. The tension of the spring in element 130 is very light so that when a loaf is pushed over the elevator platform and engages it, plate 128 is pushed to the right, as seen in FIG. 3, compressing the spring until plate 128 engages stop 132. The arc through which element 128 is actuated is very short.

A lip 129 on the lower edge of plate 128 is normally disposed slightly above and in the path of catch 136 but disengaged therefrom. When plate 128 is actuated by a loaf, the plate is moved out of the path of the elevator which is thereby enabled to rise through its full vertically displaceable distance in response to the action of its controlling cam and levers at the correct moment to engage a flight in correct phase in a manner to be described. If the plate 128 is not engaged by a loaf, the cam and lever elevator control mechanism will operate during each cycle of operation of the cam, which runs continuously, so that the cam and lever mechanism tends to raise the elevator through its full distance but will be effective to raise it only sufficiently so that catch 136 engages lip 129 whereupon further upward motion of the elevator is prevented. This will now be described.

Cam 103 controls follower 104 which is secured to crank arm 106. Arm 106 is normally urged downwardly by spring 108 which is tensioned between the frame and a pin 109 in arm 106. As best seen in FIG. 2, arm 106 is secured by means of a hub 111 to shaft 110. Shaft 110 is journaled near its opposite ends in the side of the frame. Secured to shaft 110 also interiorly of each of its ends are two hubs such as 113 each having an arm such as 112. At their right-hand ends, these arms together carry a shaft 116. The opposite ends of shaft 116 are secured in brackets 120. Another pair of arms, such as 114, are each mounted at their left-hand ends for limited rotation to a bracket such as 119 and at their right-hand ends they cooperatively carry a shaft 118 which is arranged to cooperate with shaft 116 in lifting the elevator.

The two sets of arms such as arms 112 and 114, and the elements in which they are secured at each end, form, as it were, parallelograms. Arms 112 when rotated do the lifting of the elevator and arms 114 act as stabilizers. As cam 103 rotates, follower 104 moves up and down vertically rocking arm 106, shaft 110 and arms 112, shaft 116 and lifting the elevator. Arms 114 and shaft 118 follow the motion tending to stabilize the motion. When the follower 104 is in its upper position, the elevator is in its lower position. When the cam 103 is in such position that spring 108 may draw arm 106 downwardly, arms 112, shaft 116 and the elevator are urged upwardly. If plate 128 has been displaced out of the path of the elevator, the elevator rises to its full vertical displaceable distance to present a loaf to a flight such as 78 and the loaf is pushed toward the slicing bandsaw knives. If plate 128 is not displaced, the elevator rises only slightly until further motion is arrested by engagement of catch 136 with lip 129. On each cycle of operation, obviously, cam 103 controls the elevator so that it is depressed to its lowermost position and frees catch 136 from lip 129 if it has been in engagement therewith.

The condition of an elevator as shown in FIG. 3 is the normal position of rest in which the elevator is in its lowermost position. In FIG. 4, a loaf has displaced plate 128 and the elevator is enabled to move upward through its full distance. FIG. 5 shows the condition 60 of the mechanism when the elevator has risen to its topmost position and a flight such as 78 engages the loaf. FIG. 6 shows the condition of the mechanism during one phase of a cycle in which no loaf has been received and the elevator is latched against further upward motion. It will be observed that in the particular phase of the cam operation shown in FIG. 6, the cam 103 is disengaged from its follower 104 and the mechanism is under control of spring 108 which will maintain the latch closed.

What is claimed is:

1. In a bread slicing machine, a plurality of slicing saw bands, a first continuously operated transfer having a first individual conveying element for engaging and conveying an item toward and partially through said saw bands, a second continuously operated transfer, in 75 tandem with said first transfer, said second transfer hav-

ing a second individual element for engaging and conveying said item without interrupting the remainder of the distance through said saw bands, a receiving station in said machine for receiving said items at random, an elevator at said station for presenting said item to said first element so that said first element propels said item off said elevator toward said saw bands, means for actuating said elevator, said first element and said second element in synchronism.

2. A bread slicing machine having a plurality of band slicing blades, an infeed to said slicing blades, an outfeed from said slicing blades, a first continuously operated conveyor mechanism in said infeed, a second continuously operated conveyor mechanism in said outfeed, a plurality of first and second pushers actuated by said first and second mechanisms, respectively, each of said pushers so spaced one from another is to accommodate only an individual loaf of bread, an elevator in said infeed, said elevator disposed below said first pushers and normally at rest, an elevator lift enabler in said infeed responsive to the random reception on said elevator of any loaf, an elevator lift controllable by said enabler, synchronizing means connected to said lift, responsive to said enabler, for actuating said lift to present any individual loaf to an individual first pusher in proper phase, each said first pusher disposed so as to then sweep an individual loaf off said elevator and propel it into and partially through said

blades, and other synchronizing means controlling said second pushers so that an individual one of them thereupon engages the partially sliced loaf without interruption to complete the slicing and propel it through said outfeed.

5 3. A slicing machine in accordance with claim 2 in which said first pushers are a plurality of individual flights pivotally secured at one end to a first continuously driven chain, both said chain and said flights so disposed 10 above said elevator that a flight engages a loaf at the upper portion of the rear of the loaf.

10 4. A slicing machine in accordance with claim 3 in which said second pushers are a plurality of individual elements secured to a second continuously driven chain, 15 and in which the second chain and the individual elements are disposed so that an individual element engages the rear lower portion of an individual partially sliced loaf.
